UNITED STATES PATENT OFFICE

JAMES H. EDWARDS, OF PASSAIC, NEW JERSEY, AND ROBERT A. MARBLE, OF BEN AVON, PENNSYLVANIA, ASSIGNEES TO UNITED STATES STEEL CORPORATION, OF NEW YORK, N. Y., A CORPORATION OF NEW JERSEY

ROLLED H SECTION

Application filed May 15, 1925. Serial No. 30,493.

This invention relates in general to structural members and more particularly to solid rolled sections of substantially or approximately H-shape cross-section. The invention is defined with particularity in the appended claims and the various objects and advantages thereof will be apparent from the following specification when read in connection with the accompanying drawings in which—
10 Fig. 1 is a portion of a structure including an H-column and beams embodying our invention;

15 Figs. 2 to 5 are sectional views of H-sections having novel proportions and properties hereinafter referred to.

Our invention aims to provide a solid rolled H-section, having a mean flange thickness greater than its web thickness, that will have greater strength to resist flexure in a direction parallel to its width when subjected to 20 axial compression, or to combined compression and bending, than any such rolled section of the same weight and width, or of the same weight and depth heretofore proposed or put on the market; or, conversely, the production of such a section with less width, or 25 less depth, than any hitherto offered rolled section of the same weight and with the same strength in the aforesaid direction. We also 30 aim to provide a section so proportioned that after it is surrounded by covering material a substantially smaller transverse area shall be occupied by the finished member than if any hitherto offered rolled section of the same 35 weight and strength were used.

It is a principle accepted in the structural art that the resistance of a compression member to flexure in any direction is measured by its ratio of slenderness, that is, by the ratio 40 of its radius of gyration in that direction to its unsupported length. It is also well known that in most cases the critical or weakest direction in which an axially loaded column is liable to first fail is that parallel to its 45 width. It is resistance to flexure in this direction that is considered in the embodiments of the invention illustrated and described in connection with Figs. 2 and 3.

Whichever of the purposes (or combination 50 of purposes) stated above is desired, is ac-

complished under our invention by making the width of the solid rolled section (as measured across its flanges) considerably greater than its depth (as measured between the outer faces of its flanges).

55

To the best of our knowledge and belief there has not heretofore been proposed or placed on the market any solid rolled H-section having this characteristic. We are familiar with solid rolled H-sections whose width 60 is nominally equal to the depth and which as a result of mere rolling exigencies are produced in certain weights whose width is slightly greater than the depth but in these cases the excess width does not exceed $\frac{3}{16}$ of an 65 inch. Our invention, however, is based on our discovery of the feasibility and advantage of a substantial, that is to say, a considerable excess of width over depth as explained hereinafter.

70

The effect of our arrangement is that a greater proportion of metal is disposed in the flanges where it acts with greater leverage against flexure and a smaller proportion is left in the web where its leverage would be 75 of little moment. This disposition of the metal results in a greater radius of gyration and consequently in greater strength to resist flexure in a direction parallel to the width of the section which as explained above is 80 generally the criterion.

75

To illustrate, there is now on the market an H-column 14 inches deep, 14 inches wide, and weighing 100 pounds per linear foot. Its web is .51 inch thick and its flanges have a 2 85 percent internal slope and a mean thickness of .8125 inch. Its radius of gyration parallel to the flanges is 3.504 inches.

85

In comparison, Fig. 2 represents the cross-section of an H-column covered by our invention. It has the same width, weight, flange slope and web thickness as the column above mentioned but instead of being 14 inches deep we make it, for example, 12 95 inches deep and transfer the web metal thereby saved to the flanges to which in order to keep the weight unchanged, we give a mean thickness of .8503 inch. The effect of this re-arrangement is that the radius of gyration 100

90

95

100

parallel to Z—Z now becomes 3.588 inches, an increase of 2.4 percent.

Again, Fig. 3 represents the cross-section of an H-column also covered by our invention which has the same depth, weight, flange slope and web thickness as Fig. 2 but instead of being 14 inches wide we make it, for example, 13.7 inches wide, and utilize the metal thereby saved to thicken the flanges still more, their mean thickness now becoming .8696 inch. The result is a radius of gyration of 3.516 inches which slightly exceeds that of the old 14 inch by 14 inch section referred to despite a reduction in width of 2.1 percent and a reduction in depth of 14 percent.

In the above calculations we have followed the American practice of disregarding the effect of the fillets on the radius of gyration. If this effect is considered the radius of gyration parallel to Z—Z in all three cases will be slightly lowered but the relative results will remain unchanged.

If the inside faces of the flanges are rolled parallel instead of sloping, the radius of gyration in all three cases will be increased but the relative results will remain unchanged.

As compared with present sections of approximately the same weight and depth, the greater strength of our sections is even more marked. Thus, there is now on the market a section of an H-column 12.375 inches deep, 12.12 inches wide and weighing 99.33 pounds per linear foot. Its radius of gyration is only 3.057 which is 14.8 percent less than that of the section shown in Fig. 2 proportioned according to our invention.

In addition to the greater resistance to flexure of our H-sections when considered as a whole, it should be noted that our invention results in making the flanges thicker (for the same weight and width of section) than present practice and this characteristic has the added advantage of affording greater resistance to local crippling of the outstanding flange metal. This feature is especially valuable in short columns which tend to fail by local crippling before their full resistance to flexure is exercised.

The advantage of greater strength without increase in weight is self-evident. The alternative advantage of equal strength and weight with an actual decrease in external dimensions is greater than is expressed by the percentage given above for Fig. 3, especially when the sections in question are intended for use in a fireproof building for here the customary methods of covering the column sections result in a percentage of space saved greater than the reduction in the width of the rolled section.

It is standard practice to make the covering of columns either circular or square and the saving in available finished floor space then becomes a function of the square of the

cross-sectional dimensions. Thus, allowing 2½ inches all around for the thickness of fireproofing and plaster, the external radius of the circular finished covering around the old 14 x 14 inch H-column would be 12.3995 inches, and its area 483.0 square inches. The external radius for Fig. 2 would be 11.7195 inches, and its area 431.5 square inches, a saving of 10.7 per cent. The external radius for Fig. 3 would be 11.6062 inches, and its area 423.2 square inches, a saving of 12.4 per cent.

When it is considered that owners of buildings in congested city districts, where land values are high and sunlight at a premium, are willing to pay extra for unusual forms and greater tonnages of steel in order to reduce by even a small percentage the area at each floor occupied by columns, it will be realized that the areas savable by our invention are a valuable factor in the construction of building, especially as they are accompanied by no greater weight of rolled column sections.

It is well known in the structural art that many important structures require the use of strong beam or girder sections whose depth shall be a minimum. For example, tier buildings in cities where the height of building is restricted by municipal regulation can be designed as indicated in Fig. 1 with the aid of our shallow beam and girder sections *b* and *g* so as to secure extra tiers or floors as compared with the number of floors securable if deeper beams were used. This, as illustrated in Fig. 1, is due to the consequent decrease in the net thickness *t* of each floor from ceiling of one story to finished floor surface of the next story above. This results in a decrease in the distance *D* from floor to floor while maintaining the clear distance *D*¹ from floor to ceiling. In other cases the use of shallower sections eliminates the need of girders dropping below the ceiling line thereby making feasible the adjustability of partitions in any location without marring the architectural effect and decreasing the quantity of fireproofing, plastering, or other finishing material required.

A similar advantage occurs in the floors of railroad or other bridge construction where the frequent need of a minimum difference between the over and under road grades combined with fixed headroom makes strong but shallow sections of floor beams a desideratum.

In cases similar to the above when the clear span of a beam is properly braced laterally, its strength to resist vertical flexure is determined by its section modulus about a horizontal axis.

We will now show how our invention permits an equal or greater section modulus per pound of beam combined with a shallower depth than any existing rolled section.

There is an old H-section now on the market

12.375 inches deep, 12.12 inches wide, weighing 99.33 pounds per linear foot which has a section modulus of 129.6 which is 1.3047 per pound.

5 Fig. 4 shows an H-section covered by our invention 12.348 inches deep, 14 inches wide, weighing 100 pounds per linear foot which has a section modulus of 135.37 which is 1.3537 per pound. Thus, our section although slightly shallower is 3.76 percent stronger than the old one last referred to.

10 Fig. 5 shows another H-section embodying our invention. This section is 14.154 inches deep, 15.145 inches wide, it weighs 115 pounds per foot and has a least radius of gyration of 3.89.

15 It will be noted that the additional width of our sections when used as floor beams occupies no more useful space than the narrower sections now on the market for the reason that the width is buried in the floor itself. We shall now show that this additional width is actually of further advantage.

20 25 As stated above, when a beam is properly braced laterally its section modulus is the criterion of its strength to resist flexure. If, however, it is not feasible to provide adequate lateral bracing all standard specifications stipulate that the working unit stress, by which the section modulus is to be multiplied in order to ascertain the resistance of the beam to flexure, shall be reduced by an amount that varies with the ratio of the 30 unbraced length of beam to its width. In such cases it is evident the reduction in allowable working stress for our section is less than in the case of the narrower sections now in use and consequently its available strength 35 is still greater.

40 In the above calculations we have followed the American practice of disregarding the effect of the fillets on the section modulus. If this effect is considered the section moduli 45 in question in all five figures will be slightly increased but the relative results will remain unchanged.

45 The term "structural section" used in the claims is intended to cover either column, 50 girder or beam sections particularly adapted for use in the construction of buildings, bridges and the like as distinguished from comparatively smaller sections of somewhat similar contour but not having the same 55 properties and used chiefly for small machine elements such as axles, connecting rods and the like found in arts outside of the building trade.

60 Though we have described our invention with particular reference to H-beams and columns of specific proportions and definite dimensions, it is not to be construed that we are limited thereto as certain ranges of variation can be resorted to by those skilled 65 in the art without departing from the in-

vention as pointed out in the appended claims.

What we claim is:

1. A rolled steel section of substantially or approximately H-shape in cross-section 70 weighing 115 pounds per linear foot and having the following dimensions, depth 14.154 inches, width 15.145 inches, web .551 inch thick, each of the flanges having a slight slope and a mean thickness of .882 inch. 75

2. A rolled steel section of substantially or approximately H-shape in cross-section, weighing 115 pounds per linear foot and having the following dimensions, depth 14.154 inches, width 15.145 inches, web .551 inch 80 thick, each of the flanges being .882 inch thick.

3. A rolled metal section of substantially or approximately H-shape in cross-section whose ratio of least radius of gyration divided by the depth of the section exceeds 0.27. 85

In witness whereof, we have hereunto signed our names.

JAMES H. EDWARDS.
